ATTORNEY

UNITED STATES PATENT OFFICE

SAMUEL SKOTNIK, OF BRONX, NEW YORK

CONDIMENT SHAKER

Application filed June 11, 1927. Serial No. 198,087.

The main object of my invention is to provide a useful, attractive and sanitary sprinkler or distributor for salt, pepper or other condiments or spices.

5 Another object is to provide a shaker which will not get clogged up.

Another object is to provide a simple but reliable shaker which is normally closed when not in use and which will afford a 10 spreading discharge.

Another object is to provide a construction of this character which can be readily cleared in case the condiment becomes caked.

The invention relates primarily to the top 15 or outlet member and consists primarily in the provision of a cap portion having a plurality of discharge orifices with a funnel-like outlet normally closed by an ornamental ball or closure member and the outlet is so 20 shaped and proportioned as to leave a space sufficient to permit the condiment to settle back through the orifices when the closure member is loosely connected to the cap by means of a 25 stem which projects through the center of the funnel portion and may be provided with one or more fingers on the inner end to stir up the condiment within the cap and clear the orifices in case the condiment be- 30 comes caked.

Fig. 1 is a side view of one design of shaker embodying one form of my invention.

Fig. 2 is a vertical sectional view of the outlet or discharge end shown in section on 35 an enlarged scale.

Fig. 3 is a similar sectional view showing the device inverted for discharge.

Fig. 4 is an exploded perspective view of the parts of the cap and closure.

40 Fig. 5 is a plan view of the cap alone.

The body or receptacle portion 6 may be of any suitable design or material, but is preferably provided with a neck 7 screw threaded to receive the cap 8. This cap 45 may be of any suitable material but is preferably of metal and provided with an interior screw thread 9 for engagement with the threaded neck 7. This cap is provided with an interior wall 10 which is inclined down- 50 wardly and inwardly from the rim 11, thus

forming a funnel-like space 12, with a passage 13 in the center and a series of orifices 14 and 15 arranged around the sides.

The ball or "marble" 16 is preferably 55 formed of some ornamental material or substance, such as stone or colored glass or marble preferably polished and spherical and of such a size that it neatly fits within the mouth of the rim 11, but leaving a space beneath it and above the inclined wall 10 where any of the condiment which has failed 60 to be completely discharged in shaking can collect and move to and through the passages 14 and 15 without being caught and packed down by the closure member 16. The 65 closure member has a stem 17, the outer end of which is suitably secured in the closure 16 and passes through the opening 13 in the center of the cap. This stem is preferably 70 enough smaller than the passage 13 so that it will not bind when in use. The inner end of the stem is enlarged to prevent it from dropping out when in the position of Fig. 3. This enlargement may take the form of one or more fingers 18 adapted to loosen 75 and break up the salt or other condiment by the movement of the member 16 and its stem 17. These fingers may be curved or otherwise shaped to correspond with the inner wall of the member 10 so that by rotating the 80 finger or fingers any material adhering to the wall 10 may be scraped off by simply rotating the ball 16.

Ordinarily the ball rests in the cap as shown 85 in Figs. 1 and 2 so as to prevent any dirt or moisture from getting into the receptacle and also so as to preserve any aroma which the condiment may have. When the shaker is used, of course, it will be inverted as shown in Fig. 3 at which time the closure member 90 will fall outwardly and the condiment will sift out through the passages 14 and 15 striking against the inner face of the ball member 16 and being thus spread in every direction. By having a plurality of openings 14 95 and 15 arranged in a plurality of circles, I insure the best possible delivery without depending upon the central passage 13 through which the stem 17 passes. When the receptacle is shaken the stem 17 and fingers 18 100

tend to break up any caking of the condiment which may have occurred.

When the holder is placed in its upright position the ball 16 settles back into the funnel 12, thus completely closing the mouth of the funnel but without packing down any of the condiment which may have fallen off from the bottom of the ball or which may have failed to leave the outer surface of the wall 10. I thus insure a tight, clean fitting joint between the valve member or closure 16 and the edge of the funnel 12 of the cap. Obviously, the form of design and details of construction may be changed without departing from the spirit or scope of the invention.

I claim:

1. A condiment shaker comprising a receptacle having a neck portion, a detachable cap on said neck consisting of a cylindrical body portion and a concavo-convex inner wall provided with a central opening and a plurality of perforations therearound, an inwardly extending flange formed on the upper edge of said body portion, a ball seated on said flange, a stem secured to said ball and passing loosely through said central opening to the interior of the receptacle, and concavo-convex fingers fixed to the inner end of said stem and being adapted to rotatably engage the concavo surface of said inner wall when the ball is removed from its seat, said ball and inner concavo-convex wall being so disposed relatively that a space is provided therebetween.
2. A condiment shaker comprising a receptacle having a neck portion, a detachable cap on said neck consisting of a cylindrical body portion and an inner wall provided with a central opening and a plurality of perforations therearound, an inwardly extending flange formed on the upper edge of said body portion, a ball seated on said flange, a stem secured to said ball and passing loosely through said central opening, to the interior of the receptacle, and a device fixed to the inner end of said stem and being adapted to rotatably engage the surface of said inner wall when the ball is removed from its seat, said ball and inner wall being so disposed relatively that a space is provided therebetween.

SAMUEL SKOTNIK.
